UNITED STATES PATENT OFFICE.

WILLIAM L. SCHELLENBACH, OF CINCINNATI, AND CLARENCE J. ROBINSON, OF WILMINGTON, OHIO, ASSIGNORS TO THE IRWIN AUGER BIT COMPANY, OF WILMINGTON, OHIO, A CORPORATION OF OHIO.

MACHINE FOR GRINDING BITS.

Application filed July 27, 1920. Serial No. 399,270.

To all whom it may concern:

Be it known that we, WILLIAM L. SCHELLENBACH and CLARENCE J. ROBINSON, citizens of the United States, residing, respectively, at Cincinnati, Hamilton County, Ohio, and Wilmington, in the county of Clinton and State of Ohio, have invented certain new and useful Improvements in Machines for Grinding Bits, of which the following is a specification, reference being had therein to the accompanying drawing.

This invention relates to machines for grinding bits and in particular relates to an improvement upon machines for simultaneously grinding the shanks and the grooves. In this type of machine a piece of work is rotated between a headstock and a tailstock which are carried on a carriage having a longitudinal movement on the bed of the machine. This movement is secured by the rotation of the driving element in the headstock, through a screw on the latter and a nut on the bed of the machine. On the sliding carriage is also located a grinding wheel having a transverse movement on the same: this wheel operates on the shanks only of the bit being formed, and is therefore called the "shank grinding wheel." Secured to the frame, and therefore with a relative movement to the piece of work, is a second grinding wheel, properly profiled to cut the grooves of the bit, called for that reason the "groove grinding wheel." These two wheels, the work, and the various other members are actuated or manipulated in the manner described hereafter.

The fundamental operation of such a machine is as follows: The motors being started, a piece of work is placed between the headstock and the tailstock. At the proper time, the work is started rotating and advancing across the face of the groove grinding wheel by rotation of the worm, which has the same pitch as the bit to be produced. Simultaneously the two grinding wheels are moved towards each other, and into contact with the work. Under their action the bit is reduced to shape: at the end of the travel of the work, it is automatically reversed both in longitudinal and rotational direction.

Our invention has more particularly for object the starting and stopping of the bit moving mechanism, and the simultaneous

engagement or disengagement of the groove and shank grinding wheels, by the movement of a single handle. This leaves the operator free with his other hand to manipulate other parts of the machine or to adjust the work.

Referring to the drawings, Fig. 1 is a side elevation of a complete machine embodying our invention;

Fig. 2 is a detail of the operating mechanism;

Fig. 3 is an end elevation of the operating mechanism;

Fig. 4 is an end elevation of the whole machine, to show the relative arrangement of the parts, seen from the tail stock end;

Fig. 5 is a similar view from the headstock end;

Fig. 6 is a plan of the machine;

Fig. 7 is a rear view showing the driving connections;

Fig. 8 is a detailed view, partly in section, of the driving head, with clutch elements;

Fig. 9 is a view on a large scale, showing the correlation of the clutch and the sleeve;

Fig. 10 is a similar view showing the driven and the sleeve shafts.

The machine is driven from an electric motor M on the shaft of which is a belt pulley M' and also from a second electric motor N on the shaft of which is a wheel gear driving the worm D. On the shaft of this worm is a belt pulley 96^a. These pulleys respectively drive the shank grinding wheel pulley 64 and the pulley 87 for the carriage advancing mechanism by means of suitable belts as shown in Figures 4 and 5. On the shaft of the motor N is also a pulley N' belted to the pulley 75 of the groove grinding wheel. On the transverse shaft 37 is also designated a further pulley 77 with belt transmission to a small pump 76, which serves to deliver lubricant or cooling liquid to the grinding wheels or elsewhere as desired. Inasmuch as these elements may be driven in any other manner without affecting the essence of our present invention, they have been described broadly in such a manner as to show an operative relation. It will be noted that there is no positive transmission ratio between the motors and any of the elements driven thereby; the speed of the wheels is therefore, because of

the belt slip, in no fixed ratio to the speed of the work or to each other.

The groove grinding wheel 103 is keyed on the shaft on which is secured the driving pulley 75; this shaft is carried on a carriage 110 which permits operative movement toward or from the work but none longitudinally to it.

Referring particularly to Figs. 1 and 6, 10 1 is the base or bed of the machine, 2 is a starting or stopping lever fastened by a pin 100 (Figs. 2 and 3) to a shaft 3 which is supported in brackets 101 and 102 on the bed 1 of the machine. The shaft 3 may be 15 given a partial rotation in these brackets, being actuated by the lever 2, but has no longitudinal movement. 103 is the groove grinding wheel, and 104 is the shank grinding wheel, operating on opposite sides of the 20 bit stock or work piece 105 carried therebetween by a tail stock 106 and a head stock 107. A carriage 108 has a longitudinal motion on the bed 1: the head stock, tail stock, the bar of stock between them, and the shank 25 grinding wheel are all mounted on this carriage 108 and travel with it. The shank grinding wheel is thus caused to operate at the same portion of the piece of stock, whatever be the position of the carriage. The 30 head stock 107 is composed (Figs. 6 and 8) of a standard or bracket 81, with a driving shaft 79 mounted therein. On this shaft 79 are secured two collars 80, one on either side of the standard 81, in such manner that any 35 longitudinal movement of the shaft 79 is immediately communicated to the head stock 107; and thus to the carriage, which is reciprocated from right to left, or vice versa, with the tail stock, work, and shank grinding wheel mounted thereon. As shown in 40 Fig. 8, the shaft 79 has at its outer end a worm 84 fitting in a nut 36 secured to the bed 1. A sleeve 44^a surrounding this shaft 79 is keyed to it, and is held against longitudinal movement by suitable collars 79^a at 45 its ends; from this it will be seen that sleeve 44^a does not partake in any longitudinal movement of the shaft 79. Mounted on this sleeve 44^a, and keyed thereto in such manner as to have a slight longitudinal movement relative thereto, is a sleeve 44 having clutch teeth 44^b at either end. Two further sleeves 50 42 and 88 are disposed about the shaft 79, and are loose thereon. These sleeves have 55 clutch teeth 42^a and 88^a adapted to engage the clutch teeth 44^b alternately. Reversed bevel gears 42^b and 88^b are mounted on the sleeves 42 and 88, and keyed thereto. A 60 single bevel gear 41 mounted on shaft 40 drives both bevel gears 42^b and 88^b, but in opposite directions, as will be evident from the drawings. Shaft 79 and shaft 40 are both securely held in journal bearings in a rigid member 1' secured to the bed 1 of the 65 machine. The driving pulley 87 for the

work piece 105 actuates a worm 37 meshing with a gear 39 carrying the bevel gear 41. As the pulley 87 rotates, it drives this bevel gear 41, and thus the bevel gears 42^b and 88^b, which rotate in opposite directions. Accordingly as the clutch teeth 42^a and 44^b or the clutch teeth 88^a and 44^b are thrown into engagement, the sleeve 44, and with it the sleeve 44^a keyed thereto, will be rotated in one or the other direction. The latter sleeve 75 drives the shaft 79 and the worm 84, to rotate the work before the grinding wheels. As the worm turns, it advances in the nut 36, and causes the carriage with its attached members, to move along the machine and 80 across the groove grinding wheel. It is thus apparent that the movement of the work to right or left is dependent on whether the clutch element is thrown in to the right or to the left. For this purpose a shaft 204 is 85 disposed in a convenient part of the bed or other stationary portion of the machine, with a clutch yoke 207 having shoes 89. A full-stroke mechanism comprising plunger 59, spring 60, and a cam 61 keyed thereto, 90 turns with the shaft, and serves to assure the clutch sleeve being engaged either to right or left without sticking in a central or neutral position when actuated through this mechanism. The rod 27 across the 95 front of the machine is attached to shaft 204, and serves to rock it to right or left as required: at the right end of this rod 27 are secured two dogs 56 and 55 adjustable along it, outside the supporting bracket 54. Depending from the rear end of the tail stock is an arm 26 which has an eye at its lower end surrounding the rod 27 to the rear of the dog 55. When the carriage moves forward the arm 26 engages this dog and forces the rod 27 forward with the carriage, the dog 56 acting to prevent too much movement of said rod. This action operates the clutch and reverses the machine.

Besides this automatic reversal device, 110 there is a further hand-operated mechanism provided, which throws the clutch to right or left, or locks it in a neutral position. This consists of a shaft 210 mounted in the standard 1', and having a partial rotational 115 movement. On this shaft 210 is a sleeve 215 with a shoe 216 cooperating with integral rings 209 formed on the cylindrical surface of the sleeve 44; a longitudinal movement of the sleeve 215 on the shaft 210 will shift 120 the clutch to right or left. This sleeve 215 has a triangular aperture cut in its wall at 214, forming two cam surfaces to cooperate with a pin 211 in shaft 210. It is apparent that as the sleeve 215 is in the right or 125 left position, a rotation of shaft 210 will cause the pin 211 to strike one of these cams and move the sleeve 215, and with it the clutch member 44, to the right or left; the full-stroke mechanism assures the com- 130

pletion of the movement when the shaft 210 is rocked back. If the shaft 210 is held in the "out" position, the clutch remains disengaged from either side.

5 In our improved construction, this shaft 210 is actuated as follows:

Journalled in the brackets 101 and 102 of the bed 1 of the machine is a shaft 3 extending substantially the length of the machine, and secured against longitudinal movement by suitable collars. On this shaft is mounted a handle 2, aforesaid, to rotate it for a part revolution. At the left end, and opposite the shaft 210, a crank arm 111 10 is keyed to this shaft 3. A similar crank arm 25 on the shaft 210 is connected to the crank 111 by a simple link motion 112. As the handle 2 is thrown up or down, the clutch sleeve 44 is engaged to right or left; 15 or by keeping the handle in the out position, the clutch is kept in neutral position.

The shank grinding wheel 104 and the groove grinding wheel 103 are mounted respectively on the carriages 107' and 110; 20 carriage 107' being carried on the carriage 108, and carriage 110 being on the bed 1 of the machine; this disposition enables the two grinding wheels to be moved towards or away from the work. As shown in Figs. 30 1, 2 and 3, the carriage 107' moves in a dove-tail 10, and has a pin 9 embraced by jaws 5 of an arm 109 keyed to the shaft 3 the arm 109 thus forming a rock arm. A second arm 6 depends from and is keyed

35 to this shaft 3, and is connected at 7 to a transverse link member 8 which serves to operate the groove grinding wheel 103. Therefore, as the handle 2 is thrown up or down, the grinding wheels are brought into 40 or out of contact with the work. As the arms are on opposite sides of shaft 3, the two wheels cooperate. In order to adjust the wheels so that they may strike the work at the same time, a handwheel 20 is provided 45 to adjust the relative position of the grinding wheels 103 and 104 with regard to each other. This adjustment will determine the relative position of 103 and 104 when they are brought into their closed position.

50 It will be observed that the operator has but one lever 2 to start and stop the machine and also to throw into or out of engagement the shank grinding wheel and the groove grinding wheel with the work, thus freeing him to that extent for other duties in connection with the machine.

Having thus fully described our invention, what we claim as new and desire to secure by Letters Patent, is:—

60 1. In a machine for forming bits, a bed, a carriage carrying a shank wheel, a crimp wheel, a head stock on said carriage, a tail stock, means to reciprocate said carriage transversely of the machine, driving means, 65 means to bring said driving means and re-

ciprocating means into operative engagement and to adjust the relative position between said shank wheel and crimp wheel.

2. The combination, with a bed, a shaft, brackets to support said shaft, a lever on 70 said shaft fixed thereto, a carriage on said bed, means on said carriage adapted to move the same longitudinally, a groove grinding wheel, a shank grinding wheel on said carriage, and means upon said shaft 75 for adjusting the position of said groove grinding wheel relative to the shank grinding wheel, whereby the positions of the said shank and said groove grinding wheels are determined with regard to each other by 80 the movement of said lever.

3. The combination, with a bed, a shaft, brackets to support said shaft, a lever on 85 said shaft, a carriage on said bed, means on said carriage adapted to move the same laterally thereon, a crimp wheel, a shank wheel, means on the shaft for effecting relative movements of said crimp wheels and shank wheel toward and away from each other, the latter being mounted upon said carriage, 90 a lever on the other end of said shaft, a link connected thereto at one end and at its other end to a second lever, starting and stopping mechanism connected to said second lever, whereby when said first-mentioned lever is 95 actuated the mechanism will be started or stopped and the grooved grinding wheel and the shank grinding wheel thrown into and out of operative engagement.

4. The combination, with a bed, a shaft, 100 brackets to support said shaft, a lever on said shaft, a carriage on said bed, means on said carriage and adapted to move the same laterally, a crimp wheel, a shank wheel, means on the shaft for effecting relative 105 movements of said crimp wheels and shank wheel toward and away from each other, the latter being mounted upon said carriage, a lever on the other end of said shaft, a link connected thereto at one end and at its other 110 end to a second lever, starting and stopping mechanism connected to said second lever, when said first-mentioned lever is actuated the mechanism will be started or stopped and the grooved grinding wheel 115 and the shank grinding wheel thrown into and out of operative engagement.

5. In a machine of the class described a shaft, a bracket in which one end of said shaft is journalled, a second bracket in 120 spaced relation to the first and having the shaft journalled therein, a lever thereon, a depending arm fixed thereon adjacent one of said brackets, a transverse member connected to said arm at one end and at its 125 other to a crimp wheel, a crimp wheel, a vertically extending arm splined on said shaft, a pair of jaws on the outer end of said member embracing a pin on a carriage, a second lever at the other end of said shaft, 130

a link connected thereto, a third lever, means attached to the third lever to start and stop the reciprocation of said carriage, a shank wheel mounted on said carriage adapted to reciprocate with it, whereby when the first-mentioned lever is actuated the reciprocation may be started or stopped and the grooved grinding wheel and the shank grinding wheel thrown into and out of operative engagement.

6. In a machine for grinding bits the combination of a shank grinding wheel and a groove grinding wheel to operate simultaneously upon the work, a bed, of a carriage permitting transverse adjustment of said shank grinding wheel on said bed, of mechanism for rotating and advancing a headstock with said carriage, and of means for moving said wheel, carriage and headstock and simultaneously varying said rotating and advancing mechanism.

7. In a machine for grinding bits, the combination of a shank grinding wheel and a groove grinding wheel to operate simultaneously upon the work, a shaft, an upstanding arm on said shaft connected to said shank grinding wheel, a depending arm on said shaft connected to said groove grinding wheel, whereby the actuation of said shaft simultaneously actuates both grinding wheels to bring them into or out of engagement with the work.

8. In a machine for forming bits, a transversely movable shank grinding wheel, a transversely movable groove grinding

wheel, a shaft, a lever on said shaft, an upstanding arm on said shaft, means connecting said upstanding arm and said shank grinding wheel, a depending arm on said shaft, means connecting said depending arm and said groove grinding wheel, means for rotating the work, and means connected to said shaft for controlling said rotating means.

9. In a machine for forming bits, a transversely and longitudinally movable shank grinding wheel, a transversely movable groove grinding wheel, a shaft, a lever to rock said shaft, and means to connect said shaft and said grinding wheels, whereby said wheels are simultaneously moved into and out of engagement with the work.

10. In a machine for forming bits, a transversely movable shank grinding wheel, a transversely movable groove grinding wheel, a headstock, a tailstock, a longitudinally movable carriage carrying said shank grinding wheel, said headstock and said tailstock, means for reciprocating said longitudinal movable carriage, means for moving said grinding wheels towards and from the work including a shaft, and means for disengaging said rotating and said reciprocating means, said shaft being connected to said moving and said disengaging means.

In testimony whereof, we affix our signatures.

WILLIAM L. SCHELLENBACH.
CLARENCE J. ROBINSON.
